UNITED STATES PATENT OFFICE.

EDWARD ERICKSON, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SHOE-SHAPING MACHINE.

1,267,392.

Specification of Letters Patent. Patented May 28, 1918.

Application filed October 19, 1915. Serial No. 56,783.

To all whom it may concern:

Be it known that I, EDWARD ERICKSON, a citizen of the United States, residing at Beverly, in the county of Essex and State of 5 Massachusetts, have invented certain Improvements in Shoe-Shaping Machines, of which the following description, in connection with the accompanying drawings, is a specification, like reference characters on the 10 drawings indicating like parts in the several figures.

This invention relates to machines for use in the manufacture of shoes for shaping portions of the shoe stock in such manner as to 15 improve the appearance and the durability of the finished shoe, and is of particular utility as embodied in a machine for operating upon the bottom portion of a welt shoe after the lasting operation to prepare the 20 shoe for the attachment of the welt and the sole.

In the usual operation of lasting a welt shoe the upper is wiped inwardly over the margin of the innersole around the toe and 25 the heel by the lasting instrumentalities, and is then secured in lasted position at the toe by a binding wire and at the heel by lasting tacks which are permanent and should be 30 fully driven and clenched on the metal heel plate of the last, while at the sides of the last the upper is secured in position by partially driven temporary tacks. The lasting instrumentalities operate to conform the upper to the last and to force it against the 35 lip of the innersole and into the angle between the lip and the feather edge of the innersole. In the manufacture of the better grades of shoes, however, it is frequently found desirable to use means in addition to 40 the lasting instrumentalities for molding and creasing the upper permanently in the angle between the lip and the feather edge of the innersole, particularly at the toe end of the shoe, in order that the welt may be 45 cured as closely as possible to the innersole in the welt attaching operation. The desirability of using such means for shaping the upper at the toe end of the shoe is increased by the fact that the folds or creases in the 50 margin of this portion of the upper add to the difficulty of conforming the upper to the innersole lip and feather. A machine for operating upon an upper in this manner is

disclosed in United States Letters Patent No. 1,009,721, granted upon the application 55 of James Cavanagh, Nov. 28, 1911.

In lasting and securing the upper at the heel seat the object is to conform the upper as closely as possible to the face of the inner-sole so as to provide a flat seat to which the heel end of the sole may be closely attached. It is, accordingly, the usual practice, after 60 the upper has been wiped in and secured at the heel end, to pound the heel seat with a hand tool in order to flatten the creases in 65 the margin of the upper and drive the lasting tacks down evenly and clench them securely upon the heel plate.

An important object of this invention is to eliminate the necessity for pounding the 70 heel seat by hand and to provide a machine by the use of which the heel seat beating operation and the above described operation of molding or creasing the upper may be quickly and effectively performed. To this 75 end, an important feature of the invention consists in the provision of novel means for beating the heel seat of a lasted shoe and for forming the upper in the angle between the innersole lip and the feather, comprising 80 a unitary construction and arrangement by the use of which either operation may be performed at the will of the operator and both operations may be readily performed in succession upon the same shoe. The invention is herein shown as embodied in mechanism including a tool adjustable to different 85 positions for use in performing the different respective operations. It will be understood, however, that the invention is susceptible of various embodiments and that in its broader aspects it is not limited to the illustrated 90 constructional details.

The above and other features of the invention, including certain details of construction and combinations of parts, will now be described with reference to the accompanying drawings and pointed out in the claims.

In the drawings:

Figure 1 is a view in side elevation, with 100 portions in section, of a machine in which the invention is embodied, and

Fig. 2 is a view of the machine in front elevation, with a portion in section on the line 2—2 of Fig. 1, the operative parts being 105 shown in a different relation.

In many respects the machine illustrated is similar in construction to the machine shown in the Cavanagh patent to which reference has been made. It comprises a frame 2, the upper portion of which is shown in the drawings, provided with bearings for a shaft 4 upon which are mounted a loose pulley 6 and a fast pulley 8, the frame having pivoted thereto a belt shifter 10 for use 10 in starting or stopping the machine.

Pivoted to the frame at 12 is a U-shaped rocker arm 14 which serves as a carrier for an operating tool to be subsequently described and is arranged for oscillatory movement in a vertical plane about the pivot 12 as an axis. The means for imparting operative movements to the tool carrier 14 comprises an annular series of rolls 16 mounted on a drum 18 secured to the shaft 4, and a bar 20 slidable in a vertical guideway formed in a casing 22 which incloses the drum 18. The bar 20 engages at its lower end a hardened bearing member 24 on the carrier 14, and is slightly rounded at its upper end to 20 receive the impact of the rolls 16. When the carrier 14 is in its idle position, as shown in Fig. 2, the upper end of the bar is below the path of movement of the rolls. When the carrier 14 is raised by engagement 30 of a shoe with the tool, the bar 20 is forced into position to be struck by the rolls and receives therefrom rapid percussional impulses which it imparts to the carrier. A chain 26 is provided for supporting the tool carrier in its idle position, and an adjustable stop 28 on the carrier serves by engagement with the frame 2 to limit the upward movement of the carrier and consequently the amplitude of its oscillations.

The rocker arm 14 at its forward end is bored to provide a bearing for a spindle 30 to the lower end of which is secured a shoe beating tool 32. This tool, in the form shown, is circular with a flat end face 40 adapted for beating the heel seat of a shoe and a peripheral edge of suitable shape for forming or creasing an upper in the angle between the lip and the feather edge of an innersole. The surface of the shank of the tool 32 which engages the carrier 14 is in a plane substantially perpendicular to the axis of the spindle 30, while the lower flat beating face of the tool is inclined to this axis. In consequence of this construction and the 50 arrangement of the spindle 30 in inclined relation to the line of movement of the tool, it will be apparent that rotation of the spindle 30 will serve to change the angular relation of the flat beating face of the tool 60 to the line of movement of the tool. The parts are so formed and arranged that in one position of the spindle 30 the tool will present its flat face in a substantially horizontal plane perpendicular to the line of movement 65 of the tool, as shown by dotted lines in Fig.

1, while if the spindle is turned through 180 degrees the forward edge of the tool will be directed downwardly in convenient position for engaging and forming the upper upon the feather and against the lip of an inner- 70 sole with impulses directed into the angle between the feather edge and the lip, as shown in full lines in the drawings. A handle 34 is secured to the upper end of the spindle for use in turning the spindle to adjust the 75 tool, and a spring 36 between the handle and the carrier 14 tends to move the spindle endwise so as to maintain the tool 32 in engagement with the carrier. In order to retain the tool in either of its positions of adjustment the spindle 30 carries a pin 38 which is seated partly in a recess in the face of the tool member and is arranged to engage a complementary recess in the adjacent face 80 of the carrier 14.

In the operation of the machine, with the shaft 4 rotatating and the tool positioned, for example, as shown in full lines in Fig. 1, the operator places a shoe in the position indicated and presses upwardly to move the bar 20 into position to be engaged by the rolls 16. The rolls, through the bar and the tool carrier, now impart percussional impulses to the tool to cause it to compact the upper stock and to form and crease the upper upon the feather of the innersole and in the angle between the feather and the innersole lip. During this operation the shoe is turned to cause the tool to engage all portions that it is desired to treat. After this 90 treatment of the shoe the handle 34 is turned to position the tool as indicated in dotted lines in Fig. 1, and the heel seat of the shoe is presented to the flat face of the tool to cause the margin of the upper to be pressed 95 and beaten down and the tacks to be fully driven.

The next shoe may be conveniently presented first to the heel seat beating portion of the tool, provided the tool is left in the dotted line position after treatment of the first shoe, and the tool may then be turned into position to crease the upper on the innersole margin. It will be apparent that the tool may be turned very quickly from one 100 position to the other, so that both portions of the shoe may be readily treated while the shoe is retained in the operator's hand.

Having described my invention, what I claim as new and desire to secure by Letters 105 Patent of the United States is:

1. A machine of the class described having, in combination, means for forming an upper in the angle between the lip and the feather edge of an innersole and means for beating a shoe upon the heel seat, the machine being constructed and arranged to permit the use of either of said means alternatively in substantially the same location 110 on the machine.

2. A machine of the class described having, in combination, means for forming an upper in the angle between the lip and the feather edge of an innersole and means for beating a shoe upon the heel seat, the machine being constructed and arranged for adjustment to bring either of said means alternatively into convenient position for treating a shoe.
- 10 3. A machine of the class described having, in combination, a tool adapted to beat the heel seat of a shoe and shaped also to crease an upper in the angle between the lip and the feather edge of an innersole, and means for operating said tool, the tool being adjustable to different positions for heel seat beating and for upper creasing respectively.
- 20 4. A machine of the class described having, in combination, a tool formed with a beating face adapted to operate upon the heel seat of a shoe and shaped at the edge of said face to form an upper in the angle between the lip and the feather edge of an innersole, and means for operating said tool, the tool being adjustable to present said face in either a substantially horizontal or in an inclined position.
- 30 5. A machine of the class described having, in combination, a shoe beating tool having a substantially flat beating face, and means for imparting operative movements to said tool, the tool being pivoted for manual adjustment to change the angular relation of the plane of its beating face to the line of its operative movement.
- 40 6. A machine of the class described having, in combination, a shoe beating tool arranged for movement in a substantially vertical path at the front of the machine, and means for operating said tool, the tool being adjustable manually to present its beating face in either a substantially horizontal position or on an incline sloping upwardly toward the rear of the machine.
- 50 7. A machine of the class described having, in combination, a tool carrier, a tool mounted on said carrier in position to beat downwardly upon a shoe and formed with a substantially flat face adapted to beat the heel seat of a shoe and with an edge adapted to crease an upper in the angle between the lip and the feather edge of an innersole, and means for operating the carrier to impart beating movements to the tool, the tool being adjustable relatively to said carrier to present either its flat face or its edge in position for downward beating.
- 60 8. A machine of the class described having, in combination, a tool carrier, a tool mounted on said carrier and having a substantially flat beating face, and means for operating the carrier to impart beating movements to the tool, the tool being adjustable relatively to the carrier at the will of the operator to present said face in either a substantially perpendicular or an inclined relation to the line of movement of the tool.
- 5 9. A machine of the class described having, in combination, a tool carrier, a shoe beating tool on said carrier, means for operating the carrier to impart beating movements to the tool, the tool being mounted for turning movement relatively to the carrier to change the angular relation of the plane of its beating face to the line of its beating movement, and manually operative means for turning the tool.
- 15 10. A machine of the class described having, in combination, a tool carrier, a shoe beating tool on said carrier, and means for operating the carrier to impart beating movements to the tool, the tool being mounted to turn relatively to the carrier about an axis inclined to the line of its beating movement and having a beating face inclined to the axis of said turning movement.
- 25 11. A machine of the class described having, in combination, a pivoted tool carrier, means for oscillating said carrier, a spindle mounted to turn in the carrier, and a beating tool secured to the spindle at the forward side of the carrier and having a beating face inclined to the axis of said spindle, the spindle being so arranged relatively to the carrier that in one position of its adjustment the beating face of the tool is substantially perpendicular to the line of movement of the tool and in another position of the spindle said face is inclined to said line of movement.
- 35 12. A machine of the class described having, in combination, a pivoted tool carrier, means for oscillating said carrier, a spindle mounted to turn in the carrier about an axis lying in a plane substantially perpendicular to the axis of said oscillatory movement with the spindle inclined to the direction of said movement, a beating tool mounted on the end of the spindle and having a beating face in line with and inclined to the axis of the spindle, and means for retaining the spindle in positions of adjustment substantially 180 degrees apart.
- 45 13. A machine of the class described having, in combination, a pivoted tool carrier, means for oscillating said carrier, a spindle mounted to turn in the carrier about an axis lying in a plane substantially perpendicular to the axis of oscillation of the carrier, a beating tool mounted on the end of the spindle and having a beating face inclined to the axis of the spindle, a spring tending to move the spindle in a direction to maintain the tool in engagement with the carrier, and a handle for turning the spindle to adjust the position of the tool.
- 55 14. A machine of the class described having, in combination, a tool provided with a portion for shaping an upper in the angle

- between the lip and the feather of an innersole and with another portion for beating the heel seat of the shoe, means for imparting beating impulses to the tool, and
5 means for adjusting the tool to present either said upper shaping portion or said heel seat beating portion in convenient position to operate upon a shoe presented for treatment.
- 10 15. A machine of the class described having, in combination, a tool provided with an edge portion for shaping an upper in the angle between the lip and the feather of an innersole and with another portion for beating
15 the heel seat of the shoe, and means for imparting beating impulses to the tool, the tool being adjustable either to present said edge portion in a downwardly directed position for shaping the upper or to present
20 the heel seat beating portion in a position to beat downwardly upon the shoe.
16. A machine of the class described having, in combination, a shoe beating tool pro-
- vided with a beating face for operating upon the heel seat of a shoe and with a portion 25 at the edge of said face for shaping an upper in the angle between the lip and the feather of the innersole, and means for imparting shoe beating impulses to the tool, the tool being adjustable to present said 30 beating face or said edge portion alternatively in correct relation to the direction of movement of the tool for performing the respective operations upon the shoe.
17. A machine of the class described having, in combination, a tool provided with means for beating the heel seat of a lasted shoe and with means for shaping the upper in the angle between the lip and the feather of the innersole preparatory to the attachment 40 of the welt, and means for imparting shoe beating impulses to the tool.

In testimony whereof I have signed my name to this specification.

EDWARD ERICKSON.
